Fintie Protective Case for MacBook Pro 16 Inch, posted Jan. 26, 2022 [online], [retrieved Nov. 3, 2022]. Retrieved from internet, <https://www.amazon.com/Fintie-Protective-MacBook-A2485-Release/dp/B09R782P1R> (Year: 2022).*

Primary Examiner — Bridget L Eland*Assistant Examiner* — Josiah D. Parsons(74) *Attorney, Agent, or Firm* — iPA & iPM(57) **CLAIM**

The ornamental design for a case for a computing device, as shown and described.

DESCRIPTION

FIG. 1 is a perspective view of a case for a computing device showing my new design;

FIG. 2 is a front view thereof;

FIG. 3 is a back view thereof;

FIG. 4 is a top view thereof;

FIG. 5 is a left side view thereof;

FIG. 6 is a right side view thereof;

FIG. 7 is a bottom view thereof; and,

FIG. 8 is a front view of the case in an opened position. Broken lines showing the computing device in FIG. 8 depict environment only and form no part of the claimed design. All other broken lines depict portions of the case for a computing device that form no part of the claimed design.

1 Claim, 4 Drawing Sheets(56)
